UNITED STATES PATENT OFFICE.

JAMES THOMAS SMITH, OF NEW YORK, N. Y.

UMBRELLA OR PARASOL.

SPECIFICATION forming part of Letters Patent No. 338,566, dated March 23, 1886.

Application filed September 21, 1885. Serial No. 177,711. (No model.)

To all whom it may concern:

Be it known that I, JAMES THOMAS SMITH, a citizen of the United States, residing at New York, in the county of New York and State of New York, have invented certain new and useful Improvements in Umbrellas and Parasols; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

15 My invention relates to umbrellas and parasols; and it consists of a novel arrangement and combination, with certain parts of an umbrella-shank, of a spring, which spring forms the subject of my application No. 142,789, allowed September 3, 1885.

20 My invention is illustrated in the accompanying drawings, in which Figure 1 is a view in elevation of an umbrella shank and handle; and Fig. 2, a longitudinal sectional view of the 25 same, showing my improvements applied thereto.

As in the application referred to, the spring 30 consists of a single piece of metal, A, having a curved end, *c*, secured at that end to the tubular portion of the handle B by a rivet, *d*, so as to turn thereon, and curved at the point *a*, to bear against the wall of the tube, and having the straight central portion, *b*, and an opposite curved end, *e*, which answers as a thumb-piece; but with my present invention the mode 35 of combining the spring with the handle part of the shank is completely reversed. In that application the spring-bar extends from the thumb-piece *e* up the handle toward the canopy, and is secured to the shank by the rivet *d*.

40 By my present arrangement the bar extends in precisely an opposite direction, and the rivet *d* is passed through the shank beneath the handle. Thus the rivet upon which the spring 45 works is entirely concealed by the handle when the handle is placed upon the shank, and the shank greatly strengthened at the point where the rivet is passed through it by the bearing afforded by the handle. At the opposite end of 50 the shank, above the slide or runner H, and below the notch I, which holds the ribs of the

frame, I place the same spring-bar, for holding the top open when it is spread, but also in a reversed position to that which it generally occupies. At that end the rivet *m*, which 55 holds the spring and on which it turns, is passed through the shank and through a stop-ring, L, which incloses the shank, the function of said ring-stop being to prevent the runner from passing farther up the shank. 60

It will be noted that in both instances where the shank is drilled for the rivets of the springs it is thus greatly strengthened—first, by the handle inclosing the lower rivet, and, secondly, by the metal ring-stop, thus saving two 65 drillings of the shank.

Although I have shown and described a particular form of spring-bar, it is quite evident that other forms of springs may be employed without departing from my invention, the essential feature of which consists in the mode 70 of securing a spring to the shank of an umbrella or parasol.

Having thus described my invention, what I claim is—

1. In combination with the shank of an umbrella or parasol, a holding-spring riveted at one end to the shank beneath the handle, and extending out of the slot in the shank above the handle, and the handle entirely closed, 80 concealing said rivet and forming a bearing directly against it, substantially as described. 75

2. In combination with the shank of an umbrella or parasol, a holding-spring for the runner, and a ring-stop above the runner, said holding-spring and stop secured to the shank by one and the same rivet, substantially as described. 85

3. In combination with the stick or handle of an umbrella or parasol, a runner, a stop-ring above the runner, an upper spring riveted to said stop-ring, and a lower spring for engagement with the runner, the same being riveted to the stick below the travel of said runner, substantially as described. 90

95 In testimony whereof I affix my signature in presence of two witnesses.

JAMES THOMAS SMITH.
